HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

SHEET DELIVERY MECHANISM FOR PRINTING PRESSES

Application filed May 22, 1930. Serial No. 454,719.

This invention comprises a sheet delivery mechanism in which two products of the same or of different lengths may be delivered simultaneously side by side.

This invention more particularly comprises a mechanism of the above character in which two separately operated flies are employed, means being provided for properly timing the movement of one of the flies to deliver longer or shorter products.

A practical embodiment of the invention is represented in the accompanying drawings, in which

Fig. 1 represents an end view of the multifly sheet delivery mechanism, the parts being broken away at one of the adjustable fly cams for a clearer understanding of its adjustment;

Fig. 2 represents a detail side view of the delivery mechanism, and

Fig. 3 represents a detail section taken in the plane of the line III—III of Fig. 1, looking in the direction of the arrows.

The shaft 1 of the rotary sheet carrier which is shown herein as a fly delivery reel 2, is rotatably mounted in suitable bearings 3, 4 in the side frames 5, 6, which shaft may be driven from any suitable source of power (not shown herein) through the gear 7 located in the present instance at the end of the shaft outside the side frame 5. The usual reel engaging friction rolls 8 are carried by a cross shaft 9 mounted at its ends in upward extensions 10, 11 of the side frames 5, 6 respectively. The sheet grippers 12 are carried by the cross shaft 13 which is mounted to rock in suitable bearings carried by the fly delivery reel 2. This shaft is provided with an arm carrying a stud or roller 14 which is arranged in position to be engaged by the stationary cam 15 for operating the grippers to simultaneously take the leading edges of two sheets or two groups of sheets from the cylinder 16.

A stationary cam 17 is located in position to engage the roller 14 to operate the grippers to release the leading edges of the sheets in time to allow the sheets to travel side by side down the front of their respective flies 18, 19.

The two flies 18, 19 are independently oper-

ated and are arranged side by side in position to receive the sheets from the reel 2 and deliver them in two piles on the table 20. The alined separately operated cross shafts 21, 22 of these flies 18, 19 are mounted at their adjacent inner ends in an intermediate bearing 23 and at their outer ends in their respective bearings 24, 25 in extensions 26, 27 of the side frames 5, 6. The means for independently operating these flies so that they may simultaneously handle products of the same length or of different lengths presented thereto side by side, are constructed, arranged and operated as follows:

Two rotatively adjustable cams 28, 29 are provided on the reel shaft 1 adjacent the side frames 5, 6 respectively. The fly 18 is operated by the cam 28 through its contact with the stud or roller 30 carried by the rock lever 31; which rock lever is connected by the rod 32 to a rock arm 33 on the fly shaft 21. The stud or roller 30 is held against the face of its cam 28 by the spring pressed rod 34. Similarly, the fly 19 is operated by the cam 29 through its contact with the stud or roller 35 carried by the rock lever 36; which rock lever is connected by the rod 37 with the rock arm 38 on the fly shaft 22. The stud or roller 35 is held against the face of its cam 29 by the spring pressed rod 39.

Either one or both of the cams 28, 29 may be rotatively adjusted to properly time the movement of its fly for products of a predetermined length. In the present instance the cam 28 for the fly 18 is shown as having such an adjustment by providing the gear 7, on which the cam is mounted, with an elongated slot 40 concentric with the axis of rotation of the reel shaft 1 and by providing the cam with a series of holes 41 through one of which and the slot 40 a lock bolt 42 may pass for clamping the cam in its desired rotative adjustment.

From the above description it will be seen that the leading edges of two products of the same length or of different lengths and arranged side by side may be transferred simultaneously from the cylinder 16 to the grippers 12 on the fly delivery reel. From thence these side by side products may pass to their

respective flies for delivery in two piles, side by side, on the delivery table 20. By adjusting a fly delivery cam its fly may be timed in its action to properly deliver its product of 5 any predetermined length within prescribed limits irrespective of the movement of the other fly. For instance, the fly which is to receive the shorter product will be actuated first so as to prevent the product from passing 10 too far down the fly fingers where it would be in danger of getting out of register and also becoming wrinkled or torn, it being understood that it is desirable to start the delivery movement of the fly practically simultaneously with the release of the tail end of the 15 product by its tension rollers 8.

It is evident that various changes may be resorted to in the construction, form and arrangement of the several parts without deviating from the spirit and scope of my invention, and hence I do not intend to be limited to the particular embodiment herein shown and described, but

What I claim is:—

25 1. Sheet delivery mechanism comprising two flies, means for transferring two products of the same or of different lengths side by side thereto and means for operating the flies.

30 2. Sheet delivery mechanism comprising two flies, means for transferring two products of the same or of different lengths side by side thereto and cam controlled means for operating the flies.

35 3. Sheet delivery mechanism comprising two flies, means for transferring two products of the same or of different lengths side by side thereto and separate means for independently operating the flies.

40 4. Sheet delivery mechanism comprising two flies, means for transferring two products of the same or of different lengths side by side thereto and separate cam controlled means for independently operating the flies.

45 5. Sheet delivery mechanism comprising two flies, means for transferring two products of the same or of different lengths side by side thereto and separate means for independently operating the flies, one of said means being adjustable for properly timing the movement of its fly for products of a predetermined length.

55 6. Sheet delivery mechanism comprising two flies, means for transferring two products of the same or of different lengths side by side thereto and separate cam controlled means for independently operating the flies, one of said cam controlled means being adjustable for properly timing the movement of its fly for products of a predetermined length.

60 7. Sheet delivery mechanism comprising two flies, a rotary carrier for transferring two products of the same or of different lengths side by side thereto and means for operating the flies.

8. Sheet delivery mechanism comprising two flies, a rotary carrier for transferring two products of the same or of different lengths side by side thereto and cam controlled means for operating the flies.

9. Sheet delivery mechanism comprising two flies, a rotary carrier for transferring two products of the same or of different lengths side by side thereto and separate means for independently operating the flies.

10. Sheet delivery mechanism comprising two flies, a rotary carrier for transferring two products of the same or of different lengths side by side thereto and separate cam controlled means for independently operating the flies.

11. Sheet delivery mechanism comprising two flies, a rotary carrier for transferring two products of the same or of different lengths side by side thereto and separate means for operating the flies, one of said means being adjustable for properly timing the movement of its fly for products of a predetermined length.

12. Sheet delivery mechanism comprising two flies, a rotary carrier for transferring two products of the same or of different lengths side by side thereto and separate means for operating the flies, one of said cam controlled means being adjustable for properly timing the movement of its fly for products of a predetermined length.

In testimony, that I claim the foregoing as my invention, I have signed my name this 16th day of May, 1930.

HOWARD M. BARBER.
